UNITED STATES PATENT OFFICE.

MAURICE LACHMAN, OF NEW YORK, N. Y.

METAL CAR END.

Application filed March 12, 1926. Serial No. 94,121.

My invention relates to metal car bodies wherein the car body end is made up of an assemblage of channel bars or members horizontally disposed and lying in contact with one another by their flanges the latter portions of said channel members being suitably fastened together preferably by an electric weld.

The invention is particularly useful for 10 car bodies in which the sides consist of metal plates assembled and fastened together in any desired manner but may also be employed for car bodies in which the side is otherwise constructed or in which a suitable 15 corner post is provided to which the sides and ends are suitably anchored.

My invention is particularly useful in connection with cars the sides of which comprise metal plates inasmuch as it provides 20 for the direct attachment of an integral part of the end members to the metal car side.

In carrying out my invention I provide channel bars or members of a length greater than the width of the car end and I divide 25 the flanges of the said channel members at a suitable point near the ends of said members coinciding with the corner of the car body when the parts are assembled and then bent. The bent web portion of the channel 30 at the end thereof is attached either to the car side or corner post. The flanges of the web part are also bent around being thus brought into substantial coincidence with the side of the car and preferably welded 35 or secured together to aid in the desired reinforcement of the car body corner.

In carrying out my invention I prefer to fill in the space left by the division of the flanges with suitable filler plates or members fastened to said flanges and aiding in the reinforcement at the corner of the car body all as will be hereinafter described in connection with the drawings wherein:

Fig. 1 is a vertical section through a portion of the car end on the line 1-1 Fig. 3.

Fig. 2 is a transverse section taken at right angles to Fig. 1 and on the line 2-2 Fig. 3.

Fig. 3 is a horizontal section on the line 50 3-3 of Fig. 1.

Fig. 4 is a horizontal longitudinal section of one of the flanged members with a flange thereof divided near the end of the bar or member to permit the end of the member to 55 be bent into position shown in Fig. 5.

Fig. 5 is similar to Fig. 4 but showing the end member bent.

Fig. 6 shows a chamfer or tapering of the flange on the bent portion to remove the sharp corner.

Fig. 7 illustrates a result of making the cut in one flange at right angles to the plane of the web instead of at an obtuse angle.

Fig. 8 shows the same parts with the corner chamfered or cut away.

Figs. 9 and 10 illustrate shapes of insert plates employed at the corner where two of the channel members lie one upon the other.

Fig. 11 shows the corner with said pieces in place, the flanges being shown in plan 70 and looking in the direction of the top arrow Fig. 13.

Fig. 12 is a similar view of said parts from the reverse side or looking in the direction of the lower arrow Fig. 13.

Fig. 13 is an edge view of said parts.

Each of the superposed channel members or bars constituting the end of the car has the usual web part 1 and flanges 2 each indicated in the various figures.

These members extend transversely of the car body and are secured together by their superposed flanges at any desired number of points preferably by electric welds one of which is indicated at 3. A metal sill 4 of 85

the car, formed also as a channel member or beam and to a flange of which the flange of the lower channel member constituting the end may be secured by welds or rivets as indicated at 4'.

A metal plate of the car side 90 is indicated at 5 while 6 indicates a metal floor of the car upturned at an edge 6' for attachment as indicated at 7 to the bent around web of the car end at the corner of the body and also if desired and as shown to 95

the plate 5 forming a part of the car side. Transversely extending reinforcing angle bar 9 is secured at the end of the car by one leg namely its horizontal to the end of the car floor as indicated at 10, while its other

or upright leg is suitably riveted, bolted or fastened to the web of the bottom channel member constituting the car end as illustrated at 10' Figs. 1 and 2.

The channel bars employed for the car end are of suitable length to permit the arm being bent to extend around on to the sides of the car. My invention may be and preferably is carried out by dividing one flange of each channel member on the diagonal or obtuse line 11 as

shown in Fig. 4 and the other flange on a line which forms a right angle or different angle with the web part, the points of intersection of said dividing lines with the 5 web part being in the same vertical line and being also at a point in the web which will coincide practically with the corner of the car body when the channels are assembled after bending their ends because the web 10 part will assume the positions indicated in the Figs. 5, 6, 7, 8, 11 and 12. When the channels are so bent and assembled they may be secured by their web parts to the side or other member of the car body at or near the 15 corners of said body by welds, rivets or otherwise as indicated at 7, 7'. Also the channels are so assembled in superposed relation that the flange on the edge of one channel divided and bent as indicated in 20 Fig. 5 will engage and be superposed upon the flange on the opposite edge of another channel divided and bent as indicated in Fig. 7.

To fill the opening at the corner and make 25 a flush surface at this point I provide a plate 12 for insertion in the angular opening in the lower flange of the two superposed channel members said opening being of the form indicated in Fig. 5. Said plate rests 30 upon the flange at the upper side of the lower of the two superposed channel members and upon the portion thereof projecting from the car end, and is secured thereto by riveting or otherwise as indicated at 14 35 Fig. 11. This gives a flush surface on the top of the flange extending from the car end to the portion of the flange on the car side while the portion of said plate 12 extending beyond the edge of the flange cut 40 as indicated in Fig. 7 in the upper flange of the lower channel bar affords a support for an insert or channel plate 13, Fig. 10, adapted to fill the rectangular opening such as shown in Fig. 7 and thereby give a flush 45 surface at the lower side of the superposed flanges at the corner in an obvious manner.

The riveting or other means for securing the filler 13 to the filler 12 is indicated at 15, Fig. 11. The edges of the plate 13 when in 50 position and the edges of the opening in the flange which it fills out after the cutting and bending of the same as indicated in Fig. 7 are indicated by the two dotted lines in 55 Fig. 11. Said plate 13 is shown in full line in Fig. 12 while the edges of the superposed plate of the form shown in Fig. 9 are indicated by the dotted lines in said Fig. 12. The plate 13 like the plate 12 when in position 60 has its surface flush with the surface of the flange part of the two portions of the bent channel bar projecting respectively from the plane of the car end and of the car side.

As will be seen not only do I utilize a portion 65 of the web of the channels forming the

car end or a web integral with said portions as a means for attaching or securing the end channels in position in the complete car body but furthermore by cutting the flanges at the opposite sides of each channel bar respectively at different angles so that when two channel bars are superposed a portion of the flange of one bar will be exposed in the opening made by cutting and bending the flange of the other bar I provide for inserting and fixedly securing insert plates to fill out the openings at the corners thus giving a flush surface at these points.

I claim:

1. A metal car body end consisting of 80 superposed metal channel members disposed transversely and secured together by their flanges, the ends of said members having their flanges cut near the ends of said members and having the end portions of their 85 webs and flanges bent around for fastening to a suitable support at the corner of the car body.

2. A metal car body end consisting of 90 superposed metal channel members disposed transversely and secured together by their flanges, the ends of said members having their webs and flanges bent around at the corner of the car body for attachment to a suitable support, said bent web being 95 secured directly to a plate forming a side or portion of the side of the car body.

3. A metal car body end consisting of 100 superposed metal channel members disposed transversely and secured together by their flanges, the ends of said members having their flanges cut near the ends of said members and having their webs bent around for attachment to a suitable support and filler plates secured between the portion of flange 105 on the end of the car body and the portion of said flange bent around into line with the car side.

4. A metal car body end consisting of 110 metal channel members disposed transversely and secured together by their flanges, the ends of said members having their flanges cut near the ends of said members and having their webs bent around at the corner of the car body for attachment to a 115 suitable support, the bent ends having their flanges lying in contact.

5. A metal car end made up of superposed channel members extending transversely and each cut and bent at its end to 120 extend around onto the side of the car at the corner thereof, the cut in the flange at one edge of each member being at an angle different from that at the other edge to afford an exposed surface on one flange for 125 attachment of an insert providing a flush surface between portions of the other flange.

6. A metal car end made up of superposed channel members extending transversely and each cut and bent at its end 130

- to extend around onto the side of the car at the corner thereof, the cut in the flange at one edge of each member being at an angle different from that at the other edge
- 5 to afford an exposed surface on one flange for attachment of an insert providing a flush surface between portions of the other flange, and a supplemental insert plate at-
- tached to said insert and forming a filler for the opening at the bend of the channel member to which said first named insert is secured.

Signed at New York in the county of New York and State of New York this 8th day of March, A. D. 1926.

MAURICE LACHMAN.
